UNITED STATES PATENT OFFICE.

GEORGE H. FAHRENBRUCH, OF OMAHA, NEBRASKA.

STAND.

1,326,485.

Specification of Letters Patent. Patented Dec. 30, 1919.

Application filed April 26, 1919. Serial No. 292,886.

To all whom it may concern:

Be it known that I, GEORGE H. FAHRENBRUCH, a citizen of the United States, residing at Omaha, in the county of Douglas and 5 State of Nebraska, have invented certain new and useful Improvements in Stands, of which the following is a specification.

This invention relates to new and useful improvements in signal stands and it consists in the novel features hereinafter described and claimed.

Heretofore it has been the practice when car inspectors or section laborers have been working about the tracks of a yard or at 15 switches to place a flag, in the vicinity of the entrance of the yard or switch, to serve as a warning to the engine man of an approaching engine that caution must be exercised when entering the yard or switch to prevent 20 accident. When these operations are taking place at night a lantern is used in lieu of a flag.

At such and other times it has also been the practice to place torpedoes upon the 25 track rails to serve as a warning to the engine man or train crew when the engine is approaching such places and to serve as a warning that caution should be exercised.

An object of the present invention is to 30 provide a signal stand of simple and durable structure adapted to be applied to and supported upon one of the rails in the vicinity of the entrance of the yard or switch to supersede the flag and lantern at the side of 35 the track hereinbefore mentioned.

Another object of the invention is to provide in such a stand means adapted to securely hold the stand upon the head or ball of the rail, which means is adapted to be 40 quickly manipulated whereby the stand may be positioned upon the rail or removed therefrom.

Another object of the invention is to provide in the clamping or securing means of 45 the stand an adjustable means whereby the device may be accommodated to the heads of rails of different sizes.

Another object of the invention is to provide a strong and novel clamp which may be 50 placed over the head of the rail and when adjusted adapted to have its parts drawn in close contact with the head of the rail whereby the stand is securely held in position upon the rail.

55 Still another object of the present inven-

tion is to provide a stand with a simple clamp forming a part thereof, said clamp being cheap to manufacture and construct and easy to assemble and consisting of a minimum number of parts.

With these and other objects in view the invention relates to certain new and useful improvements and combinations of parts as will be hereinafter more fully described and pointed out in the appended claims.

In the accompanying drawings:

Figure 1 is a side elevation of the signal stand showing the same applied to the head of a rail which is illustrated in transverse section.

Fig. 2 is an edge elevation of the stand.

Fig. 3 is a transverse sectional view of the stand taken on the line 3—3 of Fig. 1.

Fig. 4 is a fragmentary side elevation of the lower portion of the stand showing the 75 parts in open position whereby the stand is about to be applied to the head of the rail or removed therefrom.

As illustrated in the accompanying drawing the signal stand comprises a frame 1 80 preferably of metal. The said frame includes a vertical or depending standard 2. The frame 1 is provided at its upper portion with loops 3 which may receive the staff 4 of a flag 5. A cotter pin 6 may be passed 85 through the staff 4 and located between the loops 3 whereby the staff and flag are prevented from becoming accidentally separated from the frame. The frame 1 may also be provided with a sign panel 7 which may 90 bear any suitable legend as for instance Safety First Stop. The panel 7 is provided with hooks 8 which may receive the bail or handle of a lantern 9 indicated by dotted lines in Fig. 1. The flag may be used 95 for a signal in the day light and the lantern for a similar purpose at night or on dark or foggy days.

The standard 2 is provided at its side and in the vicinity of its lower end with a lug 10 100 having an aperture 11. A jaw 12 is fixed to the lower end of the standard 2 and is provided with a bill end 13 adapted to pass under the head of a rail 14 and at one side thereof as shown in Figs. 1 and 4 of the 105 drawing. A set or adjustable screw 15 is located at the intermediate portion of the jaw 12 and may bear against the side of the head of the rail and which serves as means for causing the device to properly receive 110

the head of the rail irrespective of its transverse breadth whereby the signal stand is securely held in position upon the rail when applied.

- 5 A jaw 16 is pivoted to the upper end of the fixed jaw 12 and is provided with a bill end 17 adapted at times, to engage under the head of the rail 14 at the opposite side thereof from that side under which the bill end 13 engages. The jaw 16 is provided at its outer side and at a point between its ends with spaced lugs 18 and a lever 19 is pivoted to said lug. The lever 19 is approximately Z shaped in edge elevation.
- 10 15 That is to say that it has off set end portions with a connecting intermediate portion. One of the off set end portions is pivoted to the lug 18 and the other off set end portion is provided with a slot 20 which is adapted to receive the lug 10 when the signal stand is in position upon the head of the rail as shown in Fig. 1 of the drawing. The aperture 11 may receive the bail of a lock 21 and thus the parts are securely held in the 20 25 position as shown in Fig. 1.

When the device is about to be applied to the head of a rail the lever 19 and pivoted jaw 16 are swung to the positions as shown in Fig. 4. The upper part of the jaw 12 is placed upon the upper surface of the head of the rail and the bill end 13 is engaged under the side of the head of the rail. The lever 19 is then swung to the position as shown in dotted lines in Fig. 1 whereby the bill end 17 of the jaw 16 is engaged under the side of the head of the rail. The lever 19 is then swung to the position as shown in heavy lines in Fig. 1 and the lock 21 is applied whereby the parts are secured and the 30 35 40 stand is held in position upon the rail. To remove the stand from the rail the operation above described is reversed.

Having described the invention what is claimed is:—

- 45 1. A signal stand comprising a frame, a jaw fixed to the frame, a set screw passing through the intermediate portion of the jaw, a second jaw pivoted with relation to the first mentioned jaw and means for locking

the pivoted jaw at a fixed position with relation to the fixed jaw and the frame. 50

2. A signal stand comprising a frame, a lug carried by the frame, a fixed jaw carried by the frame, a jaw pivoted to the fixed jaw, and a lever pivoted to the pivoted jaw and 55 having a slot adapted to receive said lug.

3. A signal stand comprising a frame, a lug carried by the frame, a fixed jaw carried by the frame, a jaw pivoted to the fixed jaw, and a lever having off set end portions 60 one of which is pivoted to the pivoted jaw and the other provided with a slot adapted to receive said lug.

4. A signal stand comprising a frame, a lug carried by the frame, a fixed jaw carried by the frame and having an inturned bill end, a jaw pivoted to the fixed jaw and having an inturned bill end, and a lever pivoted to the pivoted jaw and having a slot adapted to receive said lug. 65

70 5. A signal stand comprising a frame, a lug carried by the frame, a fixed jaw carried by the frame and having an inturned bill end, a jaw pivoted to the fixed jaw and having an inturned bill end, and a Z shaped lever pivoted to the pivoted jaw and having a slot adapted to receive said lug. 75

6. A signal stand comprising a frame, a lug carried by the frame, a fixed jaw carried by the frame and having an inturned bill end, a jaw pivoted to the fixed jaw and having an inturned bill end, and a lever having off set end portions one of which is pivoted to the pivoted jaw and the other provided with a slot adapted to receive said lug. 80

85 7. A signal stand comprising a frame, a lug carried by the frame, a fixed jaw carried by the frame and having an inturned bill end, an adjustable screw mounted at the intermediate portion of the fixed jaw, a jaw pivoted to the fixed jaw and having an inturned bill end, and a lever having off set end portions one of which is pivoted to the pivoted jaw and the other provided with a slot adapted to receive said lug. 90

95 In testimony whereof I affix my signature.

GEORGE H. FAHRENBRUCH.
